United States Patent Office

Des. 186,894
Patented Dec. 22, 1959

186,894

AUDIO-VISUAL TEACHING DESK

Bror Wm. Henrikson, Alfred C. Hoven, William S. Lindberg, and Walter E. Nordmark, Grand Rapids, Mich., assignors to American Seating Company, Grand Rapids, Mich., a corporation of New Jersey

Application March 5, 1959, Serial No. 54,862

Term of patent 14 years

(Cl. D33—7)

Fig. 1

Fig. 2

Fig. 3

Figure 1 is a front perspective view of an audio-visual teaching desk, showing our new design;

Figure 2 is a rear perspective view of the same with a television set therein elevated to a position for viewing; and

Figure 3 is a front perspective view of the same.

We claim:

The ornamental design for an audio-visual teaching desk, substantially as shown and described.
